(57) **CLAIM**

The ornamental design for a smart grip, as shown and described.

DESCRIPTION

FIG. 1 is a top perspective view of a smart grip showing an example of our new design.

FIG. 2 is a bottom perspective view of the smart grip of FIG. 1.

FIG. 3 is a right side view of the smart grip of FIG. 1.

FIG. 4 is a front side view of the smart grip of FIG. 1.

FIG. 5 is a left side view of the smart grip of FIG. 1.

FIG. 6 is a rear side view of the smart grip of FIG. 1.

FIG. 7 is a top view of the smart grip of FIG. 1.

FIG. 8 is a bottom view of the smart grip of FIG. 1.

FIG. 9 is a top perspective view of a smart grip showing an example of our new design.

FIG. 10 is a bottom perspective view of the smart grip of FIG. 9.

FIG. 11 is a right side view of the smart grip of FIG. 9.

FIG. 12 is a front side view of the smart grip of FIG. 9.

FIG. 13 is a left side view of the smart grip of FIG. 9.

FIG. 14 is a rear side view of the smart grip of FIG. 9.

FIG. 15 is a top view of the smart grip of FIG. 9; and,

FIG. 16 is a bottom view of the smart grip of FIG. 9.
